GRAPHITE GUN

Orlando D. Shonnard, Upper Montclair, N. J.,
assignor to Joseph Dixon Crucible Company,
Jersey City, N. J., a corporation of New Jersey

Application September 9, 1947, Serial No. 772,943

3 Claims. (Cl. 222—193)

1

This invention relates to a gun for ejecting dry, powdered or granular materials, such as graphite, insecticides, or pigments.

The invention has for its salient object to provide a simple, practical and efficient device of the character specified that can be economically manufactured and comprises few parts.

Another object of the invention is to provide a gun of the character specified that is compact and in which protruding parts can be folded or nested to occupy a minimum amount of space when the gun is not in use.

Another object of the invention is to provide means, in a gun of the character described, for closing the nozzle and thereby prevent accidental ejection of graphite or other powdered material and to prevent water, moisture or other foreign substance from contacting the contents of the gun when the gun is not in use.

Another object of the invention is to provide a gun of the character specified so constructed and arranged that the material ejected may be controllably directed.

Another object of the invention is to provide a gun of the character specified with simple, efficient and self-contained means to insure a clean and unobstructed nozzle bore and nozzle tube.

Another object of the invention is to provide a gun of the character specified so constructed and arranged that the powder or contents will be stored and sealed against escape except through the discharge nozzle when the gun is used.

Another object of the invention is to provide a gun of the character described so constructed and arranged as to provide wide operating flexibility and to enable the user to discharge a spot or small amount of material or a full blast.

Further objects of the invention will appear from the following specification taken in connection with the drawings which form a part of this application, and in which

Fig. 1 is a side elevational view of a gun constructed in accordance with the invention, the handle being shown in dotted lines in operative position and in full lines in folded position;

Fig. 2 is a front elevation of the gun;

Fig. 3 is a rear elevation of the gun;

Fig. 4 is a longitudinal sectional view showing the parts in position before operation of the gun;

Fig. 5 is a longitudinal sectional elevation showing the parts after they have been moved to full operative position;

2

Fig. 6 is a transverse sectional elevation taken substantially on line 6—6 of Fig. 1, looking in the direction of the arrows;

Fig. 7 is a transverse sectional elevation taken substantially on line 7—7 of Fig. 1, looking in the direction of the arrows; and

Fig. 8 is a sectional elevation showing a modified mounting for the wire closure and cleaning pin.

In the particular embodiment of the invention illustrated, the gun comprises a housing, such as the elongated barrel or tube 10, having its rear end closed by a plug 11 secured in position by screws 12 and having its front end closed by a cap 13 threaded thereon.

The cap 13 has a central bore or opening 14 surrounded by a cylindrical flange or sleeve 15 formed integral with the cap. The cap is recessed at the outer end of the sleeve 15, as shown at 16, and a T-shaped bushing 17 formed of rubber or like material is mounted in the sleeve 15 and recess 16. The bushing 17 slidably receives a nozzle tube 20.

On the outer end of the nozzle tube 20 is mounted a nozzle 25 having a tapered outlet bore 25A and a central discharge hole 26.

The nozzle tube 20 extends into a chamber 27 and in this chamber is mounted a collar or sleeve 30 which is secured in the barrel by screws 31. A packing 30A seals the front end of the seal 30.

The sleeve 30 has a reduced grooved end 32 and a flexible, compressible, imperforate tube 33 is tightly secured, as shown at one end in the groove of the end 32. The tube 33 is preferably formed of rubber or like air tight material impervious to powder or graphite. A spring 35 is disposed in the tube 33 and seats at one end at 36 against the rear end of the sleeve 30.

In the rear end of the tube or barrel 10 there is slidably mounted a member 37 and the rear end of the tube 33 is tightly secured at 38 to the front or inner end of the member 37. The member 37 may, as shown, form the closure for the rear end of tube 33 and the tube thus forms a bag or bellows. If desired, a closed end bag could be used with a motion transmitting portion formed thereon or secured thereto.

A pin or wire 40 is carried by a rod 41 which is pivoted transversely in the sleeve 30. The rod 41 extends transversely of the sleeve 30. The pin 40 extends into the nozzle tube 20 and when the tube is pushed into the barrel to the full limit of its movement the outer end of the pin 40 ex-

tends into the nozzle discharge opening 26, thus closing the nozzle and preventing discharge of the graphite or powder therethrough. The wire pin may be connected to the rod 41, as shown in Fig. 8, by forming a coil in the wire 40', as shown at 49, and bending the end, as shown at 59. In use, the tube can be pulled out to the desired extent, thus accurately directing the graphite to the desired part. This is often desirable in applying graphite to insure the placing of the graphite in the desired spot or area and preventing wastage.

A handle 42, arcuate in section, has lugs 43 pivoted at 44 to the rear end of the housing or barrel 10. The handle has an arcuate upper end 45 curved to conform to the curvature of the barrel 10 when the handle is in operative position. In order to hold the handle 42 in extended or operative position, a spring latch 48 is carried by lugs 46 on barrel 10 and engages a bayonet slot 47 formed in the rear upper edge of the handle.

The trigger for operating the gun comprises an arm 50 pivoted at 51 to a bell crank lever pivotally mounted between lugs 46. The upper end of arm 50 is bifurcated and the surface 50A engages the under surface of arm 52 and forms a stop for limiting the anti-clockwise movement of arm 50, viewing Figs. 1, 4 and 5. One arm 52 of the lever is disposed beneath the barrel or housing 10 and the other arm 53 extends upwardly through a slot 54 in the barrel and enters a vertical slot 55 in the rear end of the member or bag or bellows end 37. The inner wall of this slot is inclined from the vertical, as shown at 56. When the bag 33, 37 is retracted by the spring 35, the arm 53 is substantially aligned with the wall 56 of the slot 55 and the arm 53 forms a stop for the rearward movement of the member or bag closure 37. The lever arm 52 has a pad or buffer 58 on its upper surface engageable with the under surface of the barrel 10.

The upper end of arm 53 is rounded to cause a smooth camming action against the inclined inner end wall 56 of the slot 55.

Operation

When the gun is to be carried or is not in use, the handle 42 and trigger arm 50 can be folded, as shown in Fig. 1. If desired, the gun may be hung on a nail or hook with the handle open and for this purpose the handle 42 has a hole or opening 60.

A charge of powder or graphite is first inserted in the barrel by removing the cap 13.

When the gun is to be used, the handle 42 and trigger arm 50 are swung outwardly, as shown in Fig. 1 in dotted lines, and the handle is grasped and arm 50 pulled toward the handle.

When the spring 35 pushes bag closure 37 rearwardly, a partial vacuum is formed and air is sucked into the gun barrel or housing 10 through the nozzle into bag 33, 37. The operation of the trigger arm 50 causes the lever 52, 53 to actuate the bag closure or member 37 and compress the bag or bellows 33, 37, thus forcing the air and powder or graphite out through the nozzle.

The nozzle tube 20 can be pulled out to extended position to direct the graphite where desired, or can be pushed in to the desired extent, care being taken not to push it in sufficiently to cause the rod or pin 40 to close the nozzle. When

the gun is not in use, the nozzle tube may be pushed in to its inner limit of movement to close the nozzle bore 26.

The pushing in of tube 20 insures the cleaning of the bore of nozzle and nozzle tube 20 of any foreign matter that may be sucked in when the bag closure and bag are retracted by the spring.

Although one specific embodiment of the invention has been particularly shown and described it will be understood that the invention is capable of modification and that changes in the construction and in the arrangement of the various cooperating parts may be made without departing from the spirit or scope of the invention, as expressed in the following claims.

What I claim is:

1. A gun comprising a barrel, a flexible, elongated tubular sack having a fixed open end facing the outer end of the barrel and fixed in the barrel intermediate the ends thereof, and a closed end slidable in the barrel toward the fixed end of the sack, resilient means for forcing the inner closed end of the sack to retracted position at the rear end of the barrel, a nozzle at the front

end of the barrel, a trigger, and means actuated by the trigger for collapsing the tube by forcing the closed end of the sack toward the nozzle end of the barrel.

2. A gun comprising a barrel, a flexible, elongated tubular sack having a fixed open end facing the outer end of the barrel, a slideable closure secured to the inner end of the sack, resilient means for forcing the inner end of the sack and closure to retracted position at the rear end of the barrel, a nozzle at the front end of the barrel, a trigger, and a lever actuated by the trigger and engaging the closure for collapsing the sack by forcing the closed end of the sack toward the nozzle end of the barrel.

3. A gun comprising a barrel, a flexible, elongated tubular sack having its outer end open and inner end closed, the open end being fixedly secured within said barrel and the closed inner end being secured to a piston, said piston being slidably mounted in the rear or inner end of the barrel, a lever having an arm extending into the barrel and engaging a rear portion of the piston and having an arm extending outside of the barrel, said lever being pivotally mounted on the barrel, and means for actuating said lever and resilient means for retracting the piston and lever to operative position after operation thereof.

ORLANDO D. SHONNARD.
